Application December 31, 1948, Serial No. 68,689

3 Claims. (Cl. 313—303)

This application relates to electron discharge devices, and more particularly to that type of device used in converting signals from one frequency to another, for example, the first detector of a superheterodyne receiver.

Frequency converters of the single tube type such as pentagrid converters have several disadvantages. Firstly, the screen grid draws a considerable amount of current and thereby produces a good deal of noise. This is necessary since the screen grid operates to form a cloud of electrons around itself so that it may behave as a second cathode. Further, the plate resistance of this type of tube is low compared to that of a pentode; hence the gain of the converter is low.

A more ideal system comprises a pentode mixing stage and a separate triode oscillating stage for producing the heterodyning oscillations. However, in addition to the use of an extra tube, this circuit presents difficulties in effectively coupling from the triode oscillator into the pentode mixer stage.

Therefore, it is an object of the present invention to produce a frequency converting device which requires less power than was heretofore possible.

It is a further object of this invention to produce a single tube frequency converting device having a high conversion gain.

Still another object of this invention is to produce a single tube frequency converting device which generates less noise than previous designs.

Another object of this invention is to produce a single tube frequency converting device wherein the gain is constant over a wider range of operation than was heretofore possible.

Other and further objects of this invention will become apparent as the description thereof progresses with reference to the accompanying drawings wherein:

Fig. 1 is a vertical sectional view of a tube built in conformance with my invention taken along section line 1—1 of Fig. 2;

Fig. 2 is a cross-sectional view of the tube taken along section line 2—2 of Fig. 1;

Fig. 3 is a cross-sectional view taken along section line 3—3 of Fig. 1;

Fig. 4 is a cross-sectional view taken along section line 4—4 of Fig. 1;

Fig. 5 is a circuit diagram illustrating a method of utilization of a tube built in conformance with my invention; and

Fig. 6 is a graph illustrating characteristic curves of operation of a tube built in conformance with my invention.

Referring to Figs. 1—4 there is shown an electron discharge device comprising a pentode section 10 and triode section 11 enclosed in an evacuated envelope 9.

While not absolutely necessary, it is preferable that both the triode section 11 and the pentode section 10 operate from a common electron source, here shown by way of example as the filament structure 12.

2

The filament structure 12 consists of two spaced parallel wires which are supported in the following manner. At the lower end of the tube is a Y-shaped yoke 12a having one of the filament wires attached to each of its upwardly extending arms. The downward extending leg of the Y-shaped member 12a is attached as by welding to a lead-in wire 4 which extends through a pressed glass seal 21 in the envelope 9 of the tube.

Filament wires 12 pass through a diamond-shaped hole in a lower support member 18 which consists of a flat mica plate. The filament wires are positioned in opposite corners of the diamond-shaped hole in plate 18, and the distance between said corners is slightly less than the distance between the wires at their point of attachment to the Y-shaped yoke 12a, thus urging the wires into their respective corners of the diamond-shaped hole. The wires 12 extend vertically throughout the length of the tube structure and pass through a diamond-shaped hole in an upper mica support plate 17 which is similar to the lower member 18. The diamond-shaped hole in the upper support member 17 is positioned directly over the hole in the lower support members and the wires passing through the hole in said upper support member are positioned in opposite corners corresponding to those of the hole in the lower support member 18.

Each of the wires is resiliently stretched by means of a spring 13. This spring 13 is a torsional spring and has one end attached as by welding to a support tab 13a which is pressed around the end of the particular wire 12. The spring 13 is mounted on a rod 13b which is attached to a support 15 consisting of a channel-shaped member extending the length of the tube structure and through the upper and lower support members 17 and 18. The lower end of the channel-shaped member 15 is welded to a lead-in wire 1 extending through the glass press 21. The spring 13 is wound slightly and the end not attached to support tab 13a is welded to the channel-shaped member 15, thus exerting a longitudinal pull on its respective wire 12. The other wire is supported by a similar spring arrangement having a separate spring and support tab 13 and 13a, but a common mounting bar 13b and channel member 15.

The springs are so supported on the mounting bar 13b that they stretch the wires, and urge the top ends of the wires into their respective corners of the diamond-shaped hole in the upper support member 17. It may be seen that, if a potential is applied between the lead-in members 1 and 4, a current will flow through the filament structure 12, heating the same.

Obviously, any number of filament wires 12 can be used. In general, increasing the number of filament wires increases the transconductance of the tube but also increases the required filament heating power.

The triode plate comprises a bar 16 connected to a lead-in wire 2, and supported between an upper mica support piece 17 and a lower mica support piece 18 parallel to filament wires 12. A flat plate 19 is welded to this bar along its length, between said bar and the filament wires 12, said plate having its flat surface parallel to the plane of said filament structure 12. Surrounding this plate structure is the grid network 14 which consists of a spirally wound wire supported on two rods 20 which in turn are supported by a press fit through holes in the upper and lower mica pieces 17 and 18. The spiral wire of the grid 14 is welded to the two supporting rods 20. One of the rods 20 is attached to an electric lead-in connector 3 which passes through the glass seal 21.

The aforementioned channel member 15 is positioned on the opposite side of the plate and grid structure 14 and 16 from the filament structure 12.

On the opposite side of the filament 12 from the triode section 11 is the pentode section 10. The grid network 22 of the pentode structure is supported by a pair of rods 23 which are supported by the mica end members 17 and 18 and positioned on either side of the filament 12 and parallel therewith. Stretched between these rods on the side of the filament opposite the triode section are the series of equally-spaced parallel wires which form the network of the grid 22. One of the rods 23 is connected to a lead-in member 5.

Adjacent to grid structure 22 and on the opposite side thereof, from the filament 12, there is a screen grid structure comprising another pair of rods 24 around both of which is wrapped a wire to form a screen grid network 25. Both the wires of the grid structure 22 and the screen structure 25 are welded to their respective rods. One of the rods 24 is secured to a lead-in conductor 6.

Adjacent the screen grid structure 25 and on the opposite side thereof, from the grid structure 22, there is a suppressor grid 26, comprising a channel-shaped member having a rectangular slot 26a cut in the bottom of the channel 26. The suppressor grid 26 is supported by the mica end pieces 17 and 18 and has the sides of its channel shape extending toward the rods 24. The suppressor member 26 is tied to the filament below the bottom mica support 18 by a strap 27.

Adjacent the suppressor grid 26 and on the opposite side thereof, from the screen grid structure 25, there is a plate electrode 28 which is similar to the support member 15 on the opposite side of the triode structure. This plate electrode 28 is a channel-shaped member slightly smaller than 26 and having no hole in its channel shape. The sides of the channel extend toward the rods 24. The plate 28 is attached at its bottom end to a lead-in member 7 and is supported by the end pieces 17 and 18.

The holes in the upper and lower mica support members which engage the suppressor grid 26 and plate electrode 28 consists of a modified H-shape. The two upright legs of the H are slightly triangular, and engage tabs on the suppressor grid 26 and plate 28, respectively. The crossbar of the H is quite thick and the purpose of the hole configuration is to produce a firm frictional fit between the electrodes 26 and 28, and the mica support pieces 17 and 18. The electrode 15 on the opposite side of the tube from plate 28 engages diamond-shaped holes in the mica support 17 and 18 to produce another frictional fit, while the rods 16, 20, 23 and 24, which support various grid and plate structures frictionally engage round holes in the mica support pieces, thereby rigidly maintaining proper spacing between the various elements.

Above the upper support member 17 there is a getter strap 29 which is welded to an upper tab of the plate 28 and bent to extend over the tops of the other electrodes in the system. This strap contains getter material, in two small detents 30 in the strap, which is used during the manufacture of the tube to clean up undesired gases in the interior of the tube.

While the electron source herein shown consists of two filament wires which are spaced slightly apart, it is to be understood that any number of wires could be used, or indeed a cathode of the indirect heater type can be used. Further, the particular details of the structure described herein which are used to produce tubes of the subminiature type are by way of example only, and any size tube with various modifications in the spacing, position, and number of electrodes can be used.

Briefly, the operation of the system of the two sections is as follows.

The pentode section 10 is connected as an R. F. amplifier and the triode section 11 is connected to a separate oscillatory circuit.

The grid 14 is very close to the plane of the filament structure 12; for example, a spacing of .010" therebe-

tween produces good operating characteristics for the subminiature tube herein described. Now due to the proximity of the grid structure 14 of the triode 11 to the filament 12 and to the space between the filament 12 and the first grid structure 22 of the pentode section 10, fields produced by voltages on the grid structure 14 of the triode section 11 will control the current to a substantial degree in the pentode section 10. Thus it may be seen that voltages in the triode section will modulate signals being amplified in the pentode section. This effect, of one element in one section of a tube exerting a control over the current flow in another section of the tube, may be termed interaction control, and the term interaction control is so defined wherever it appears throughout the specification and claims.

Referring now to Fig. 5 there is shown a circuit diagram of a frequency converter using this tube. In this system a signal is received on antenna 31 and fed through an R. F. transformer T₁ to the grid 22 of the pentode section 10 of the tube. The secondary of the transformer T₁ is tuned by a variable condenser 32 connected thereacross. The screen grid 24 of the pentode section is connected to B+. The plate 28 of the pentode section is connected through a primary of an I. F. transformer T₂ to B+. The I. F. transformer T₂ may be tuned to any desired frequency, for example, the standard 455 K. C. I. F. band, by condensers 36 and 37 connected across the primary and secondary windings, respectively, of said transformer.

30 A suitable potential A+ is applied across the filament 12, one side of which is grounded. The plate 16 of the triode section 11 is connected to B+ through the primary of a feed-back transformer T₃. The secondary of the transformer T₃ is connected from ground through a D. C. blocking condenser 33 to the grid 14 of triode section. The grid 14 of the triode section is connected to ground through a suitable grid leak resistor 34 of, for example, 50,000 ohms. The secondary of the transformer T₃ is tuned by a variable condenser 35 connected thereacross which is ganged to the variable condenser 32 for tracking the tuning of the R. F. and oscillator circuits in conformance with standard superhetrodyne receiver practice.

45 The grid 22 of the pentode 10 is connected to ground through the secondary of the transformer T₁. This grid might be connected to an automatic volume control buss through the secondary transformer T₁ rather than to ground since this tube exhibits variable conversion gain characteristics.

50 It may be seen from the circuit that the triode section 11 has no external alternating frequency connection with any of the electrodes of the pentode section. Rather the grid 14 of the triode section produces a field which extends into the space between the filament 12 and the grid 22 of the pentode section, thus coupling oscillations from the triode section into the pentode section. This coupling is sufficient that, with approximately twenty-five volt bias on the grid section 14, the pentode section is substantially cut off. Therefore, when the R. M. S. oscillating voltage in the triode section reaches approximately twenty volts, 100% intermodulation occurs in the pentode section, thus heterodyning the frequency generated in the oscillating triode section 11 with the incoming frequency from the antenna 31. Condensers 32 and 35 are so ganged 55 that the difference frequency between the incoming frequency to the grid 22 and the oscillating frequency of the triode section 11 is equal to an intermediate frequency to which the I-F. transformer T₂ is tuned. Therefore, signals coming in from the antenna 31 are converted 60 to an intermediate frequency.

65 Referring now to Fig. 6 there is shown a plot of the operating characteristics of a tube built in conformance with this invention. Along the ordinate of the graph there is plotted the root means square voltage of the 70 oscillator frequency appearing on the grid 14 of the triode

section 11. On the abscissa scale on the left of the graph there is plotted conversion transconductance G_c in microohms. This is shown by curve 35.

It may be seen that curve 35 remains substantially constant at a value of approximately 90 microohms for all values of the oscillating voltage above 16 volts. Since conversion transconductance multiplied by the total load resistance, which is equal to the plate resistance of the pentode in parallel with external resistance of the pentode plate circuit, equals the gain of the converter stage, curve 35 shows the characteristic of the gain of the converter with respect to the oscillator voltage. This gain remains substantially constant over the range above 16 volts of the oscillator. However, as shown by the dotted line 37, which represents the characteristic transconductance of a pentagrid converter circuit, this gain drops down after a peak has been reached with the result that there is no region over which constant gain may be had. Therefore, applicant's improved converter may be manufactured in large quantities, with a considerable variation in the values of the component parts, and still result in a product wherein all the converter stages have the same gain. This is due to the fact that, while variation in circuit components such as transformers, condensers, and resistors affect the magnitude of the oscillator voltage, this variation in oscillator voltage will not affect the gain of the stage if the oscillator voltage is normally designed to operate well out on the flat portion of the curve 35, for example, at a normal oscillator voltage of 25 volts R. M. S.

Curves 38, 39 and 40 are curves of the oscillator plate current, the pentode plate current, and the pentode screen current, respectively. The abscissa scale for these curves is found on the right-hand side of the graph and is plotted in milliamperes. It may be seen that the total of the currents of these curves is extremely low, less than .7 mil, for all values of the oscillator voltage.

Other and further modifications to this invention will be apparent to those skilled in the art without departing from the spirit or scope of the invention. For example, any desired oscillator circuit may be used such as a Hartley, or Colpitts, and any desired number of electrodes may be used in either the oscillator or converter sections of the tube. Further, the interacting field may be produced by other electrodes than the oscillator grid, for example, an oscillator plate screen grid, suppressor grid, cathode, or any other electrode in the oscillator section.

Therefore, applicant desires a broad interpretation of the claims commensurate with the scope of the invention within the art.

What is claimed is:

1. An electron discharge device comprising a plural filament cathode having elements lying generally in a first plane, a first anode and grid support means on opposite sides of said first anode all disposed generally in a second plane substantially parallel to said first plane, a second anode lying to the opposite side of said cathode from said second plane, a control grid mounted on said support means and being bowed in shape to dispose an intermediate curved portion closely adjacent said cathode between said cathode and said first anode and having no

part between said cathode and said second anode, the proximity of said control grid to said cathode being such that its normal control field extends into the region between said cathode and said second anode and thereby it controls the flow of electrons to both of said anodes.

2. An electron discharge device comprising a plural filament cathode having elements lying generally in a first plane, a first anode and grid support means on opposite sides of said first anode all disposed generally in a second plane substantially parallel to said first plane, a second anode lying to the opposite side of said cathode from said second plane, a control grid mounted on said support means and being bowed in shape to dispose an intermediate curved portion closely adjacent said cathode between said cathode and said first anode and having no

part between said cathode and said second anode, and proximity of said control grid to said cathode being such that its normal control field extends into the region between said cathode and said second anode and thereby it controls the flow of electrons to both of said anodes, said grid having an additional part extending between said supports across the side of said anode away from said cathode.

3. An electron discharge device comprising a plural filament cathode having elements lying generally in a first plane, a first anode and first grid support means on opposite sides of said first anode all disposed generally in a second plane substantially parallel to said first plane, a second anode lying to the opposite side of said cathode from said second plane, a first control grid mounted on said first support means and being bowed in shape to dispose an intermediate curved portion closely adjacent said cathode between said cathode and said first anode and having no part between said cathode and said second anode, the proximity of said first control grid to said cathode being such that its normal control field extends into the region between said cathode and said second anode and thereby it controls the flow of electrons to both of said anodes, second grid support means disposed on opposite sides of said cathode in said first plane, and a second control grid mounted on said second support means and extending between said cathode and said second anode.
